UNITED STATES PATENT OFFICE.

CLAUD E. FULLER, OF KANSAS CITY, MISSOURI.

BRICK AND METHOD OF MAKING SAME.

1,261,114.

Specification of Letters Patent.

Patented Apr. 2, 1918.

Application filed May 17, 1916. Serial No. 98,047.

To all whom it may concern:

Be it known that I, CLAUD E. FULLER, a citizen of the United States, residing at Kansas City, in the county of Jackson and 5 State of Missouri, have invented a certain new and useful Improvement in Bricks and Methods of Making Same, of which the following is a specification.

My invention relates to improvements in 10 bricks and methods of making same.

The object of my invention is to provide an improved method in making brick by which a brick will be produced which may be easily impregnated with asphalt or similar 15 bituminous material.

Another object of my invention is to provide a novel method for roughening the edges of a brick, so that when laid flatwise in a pavement, grouting will interlock the 20 adjacent bricks.

Still another object of my invention is to provide an improved method of making brick consisting in transversely grooving the edges thereof and then impregnating 25 the brick with a bituminous material, such as asphalt, whereby, when the brick is laid in a pavement, flat side up, the grooves in the edges will be vertically disposed, so as to permit the ready entrance of grouting 30 and the passage therefrom the full depth of the brick, the grooving of the edges further serving to permit ready impregnation of the brick with asphalt, the latter serving among other functions to prevent the crumbling 35 and breaking away of the grooved edges under traffic conditions. My invention provides further a brick made by the above described method.

Other novel features of my invention are 40 hereinafter fully described and claimed.

In the accompanying drawing which illustrates an apparatus for carrying my invention into effect,

Figure 1 is a perspective view of a die, 45 such as is commonly employed for forming a clay ribbon in the manufacture of brick, the die being provided with means for longitudinally grooving each of the sides of the ribbon.

Fig. 2 is a front elevation of the die and 50 grooving mechanism shown in Fig. 1.

Fig. 3 is a perspective view of a brick made in accordance with the principles of my invention.

Similar reference characters designate 55 similar parts in the different views.

1 designates the die of an ordinary brick machine adapted for the making of a rectangular clay ribbon 2 and provided with the usual rectangular opening 3.

As usually constructed, the sides of the opening 3, through the die 1 are polished so as to permit the clay to be readily forced therethrough. As a result, the four sides 60 of the ribbon 2 are very smooth and compact, the pores of the clay on the sides of the ribbon, thus being closed.

After the ribbon 2 has been formed, it is severed transversely in a well known manner to form bricks, the four edges of which 70 by reason of the passage of the clay against the smooth lubricated surface of the die, are very smooth and the pores closed. When such bricks are laid flatwise in a pavement, the grouting does not firmly interlock them 75 together, and furthermore, owing to the pores of the four edges of the brick being closed, such a brick is not readily impregnated by immersion in liquid asphalt.

In order that such edges may be made to 80 readily absorb bituminous material, such as liquid asphalt, and in order that when the brick thus impregnated are laid in a pavement, flat side up, they will be firmly interlocked, by grouting between them, my im- 85 proved method provides for roughening the four edges of the brick. To permit the ready entrance between the bricks after they have been laid in the pavement, my improved method contemplates providing at each edge with a plurality of transverse grooves 4, which, when the brick 5, shown in Fig. 3, is laid in the pavement, are disposed vertically, thus permitting the ready passage of the grouting the full depth of 90 the brick.

For the purpose of providing the four sides of the clay ribbon 2 with the parallel longitudinal grooves 4, there are provided four sets of transversely disposed pins 6, the 100 sets of pins being respectively mounted in four plates 7 respectively disposed parallel with the four sides of the ribbon and respectively supported by four pins 8 respectively extending through four lugs 9 provided on 105 the die 1 respectively adjacent to the sides of the die opening 3.

The pins 6 extend inwardly to points in

which they will groove the adjacent sides of the ribbon 2 as the latter emerges from the die. The scratching effect of the pins 6 breaks up the smooth sides of the ribbon and 5 thus opens the pores thereof.

After the ribbon 2 has been grooved in the manner described, it is transversely severed in any well known manner so as to form 10 bricks corresponding to the brick 5 shown in Fig. 3.

The bricks are then immersed in a suitable filling material, preferably a liquid which solidifies at ordinary temperatures, and which may be a bituminous material, such as 15 asphalt. When so immersed, the roughened or grooved edges of the brick provide for the ready passage into the pores of the brick of the impregnating liquid. The impregnating material in turn increases the adhesive 20 qualities of the particles composing the brick, and thus prevents the crumbling and breaking up of the edges adjacent to the upper side of the brick.

Modifications of my invention, within the 25 scope of the appended claims, may be made without departing from the spirit of my invention.

What I claim is:—

1. The method of making brick consisting 30 in forming a ribbon of clay by forcing the same through a die, then roughening one side of the ribbon, then transversely severing the ribbon to form bricks, and then impregnating with a bituminous material the 35 bricks so formed.

2. The method of making brick consisting in forming a ribbon of clay by forcing the same through a die, then longitudinally forming in each side of the ribbon a plu-

rality of longitudinal rough grooves, then 40 transversely severing the ribbon to form bricks, and then impregnating the bricks with a bituminous material.

3. The method of making brick consisting in forming a ribbon of clay by forcing the 45 same through a die, then roughening the sides of the ribbon, then transversely severing the ribbon to form bricks and then impregnating the bricks with asphalt.

4. The method of making brick consisting 50 in forming a ribbon of clay by forcing the same through a die, then longitudinally grooving with a plurality of longitudinal rough grooves each side of the ribbon, then transversely severing the same to form 55 bricks, and then impregnating the bricks with asphalt.

5. The method consisting in immersing in bituminous material a brick having a transversely rough grooved porous surface. 60

6. The method consisting in immersing in bituminous material a brick having a roughened porous surface.

7. The method consisting in immersing in asphalt a brick having a transversely rough 65 grooved porous surface.

8. A brick provided with a roughened porous surface and impregnated with bituminous material.

9. A brick provided with a rough grooved 70 porous surface and impregnated with bituminous material.

10. A brick having one edge transversely rough grooved and porous and impregnated with asphalt. 75

In testimony whereof I have signed my name to this specification.

CLAUD E. FULLER.
